CLAIM

The ornamental design for a light fixture, as shown and described.

DESCRIPTION

FIG. 1 is a bottom, front, right-side perspective view of the light fixture in a mounted state;

FIG. 2 is a bottom, front, right-side perspective view of the light fixture in an un-mounted state;

FIG. 3 is a right-side elevational view thereof, the left-side elevational view (not provided) being a mirror image thereof; and,

FIG. 4 is a bottom plan view thereof.

The broken lines depict environment and form no part of the claimed design.
